T. F. Bourne

UNITED STATES PATENT OFFICE.

FRANK S. TOWNSEND, OF PASSAIC, NEW JERSEY, ASSIGNOR TO PASSAIC METAL WARE COMPANY, OF PASSAIC, NEW JERSEY, A CORPORATION OF NEW JERSEY.

DISPLAY-STAND.

1,192,957.

Specification of Letters Patent.

Patented Aug. 1, 1916.

Application filed April 22, 1915. Serial No. 22,987.

To all whom it may concern:

Be it known that I, FRANK S. TOWNSEND, a citizen of the United States, and resident of Passaic, in the county of Passaic and 5 State of New Jersey, have invented certain new and useful Improvements in Display-Stands, of which the following is a specification.

My invention has reference to a simple 10 and efficient device adapted to display goods for sale or for other purposes, and the object of my invention is to provide a display stand that shall be cheap to manufacture, simple in construction, enabling the parts 15 readily to be assembled, and which will hold the articles for display in an attractive and safe manner.

In accordance with my invention I provide a display stand comprising two main 20 members, one of which is adapted to retain the articles to be displayed, the other of which serves as a base or support for said retaining member, complementary interengaging parts being provided upon said members, one of said members having a portion 25 adapted to bear against the other member to retain said complementary portions together, whereby the members may be assembled and so retained in a simple and expeditious manner.

My invention further comprises novel details of improvement and combinations of parts that will be more fully hereinafter set forth and then pointed out in the claim.

Reference is to be had to the accompanying drawings forming part hereof, wherein,

Figure 1 is a perspective view of a display stand embodying my invention; Fig. 2 is an enlarged detail section on the line 2, 2, 40 in Fig. 1; Fig. 3 is a detail section of a portion of the base member, and Fig. 4 is a detail perspective view looking at the lower end of the upper member of the stand.

Similar numerals of reference indicate 45 corresponding parts in the several views.

The numeral 1 indicates an upper or main member of my improved stand and 2 indicates a lower or base member of the stand adapted to receive and support the member 50 1 in the desired position. The member 1 may be made in a single piece of sheet metal or other suitable material, and is shown comprising a rear or back wall 1^a having sides 1^b bent substantially at right angles to said 55 wall, providing a compartment or chamber

for the articles to be displayed, which compartment or chamber is shown open at the front and top. At 3 said member 1 is shown provided with a bottom wall for said compartment or chamber upon which the articles may rest. Said bottom wall may be made by bending the blank for member 1, so as to pass between the sides 1^b at their lower portion, the material at the forward edge of said bottom wall 3 being shown bent 60 downwardly at 4. In the arrangement illustrated the lower edges of the sides 1^b are inclined with respect to the plane of the rear wall 1^a, as indicated at 1^c, so as to rest upon the bottom 2^a of the base member 2, whereby 65 member 1 may be retained in an inclined position with respect to member 2, the lower edge of the part 4 substantially coinciding with the bottom of member 2. Said base member 2 is shown comprising the bottom 2^a and sides 2^b uprising therefrom, adapted to receive the member 1 between them, with said member resting upon said bottom. Complementary fastening devices are provided 70 between members 1 and 2 to secure them together. For this purpose I have shown the bottom 2^a provided with a tongue or finger 5 struck out from the material of the bottom 2^a, and extending forwardly under the bottom wall 3 of member 1, and passing 75 through a loop or bar 6 that is struck out and pressed downwardly from bottom wall 3 of member 1. The forward edges of the sides 2^b of base member 2 are shown provided with lugs or lips 7, which are adapted 80 to be folded in front of the wall portion 4 of member 1, to retain said members locked together by the tongue and loop 5, 6.

When the members are to be assembled the lugs 7 are unfolded, the upper member 1 is 85 placed within the base member 2, and then by a relative movement of said members the tongue 5 is caused to pass through loop 6 to fit the parts together, and then the lugs 7 are bent inwardly or toward each other in 90 front of the wall part 4 of member 1, as illustrated in Fig. 1. Such bending of the lugs in front of part 4 prevents member 1 from sliding forwardly out of member 2, and the tongue and loop 5, 6, prevent member 1 95 from sliding rearwardly in member 2, and said lugs and tongue and loop prevent member 1 from being pulled upwardly out of member 2. One or more lugs 7 may be provided as may be desired.

The construction described enables a relatively cheap display stand of the character described to be produced, and one which may be readily assembled, without special skill, the cost of the device thereby being materially reduced. Furthermore, the construction enables the parts to be shipped in a knockdown or dis-assembled condition and to be readily assembled by unskilled persons. Any suitable advertising matter may be produced upon the parts of the stand, and the same may be decorated in any manner to afford a pleasing effect.

Having now described my invention what

15 I claim is:—

A display stand comprising an upper member having a rear wall and sides projecting forwardly therefrom and having a bottom wall, said walls and sides providing 20 a receptacle for exposing articles therein, the lower edges of the sides being inclined with respect to the rear and bottom walls, the bottom wall having a front portion pro-

jecting downwardly, said bottom wall having a loop struck out downwardly from the 25 rear portion thereof, and a base member having upturned side walls adapted to receive the main member therebetween, the bottom of said base member having a tongue struck up therefrom adapted to coact with said 30 loop, one of said side walls of said base member having a flexible lug adapted to be bent to extend in front of said front portion of the first named member after the parts have been assembled to retain said tongue and 35 loop in coactive relation, said lug preventing tilting of the upper member out of the base member.

Signed at Passaic, in the county of Passaic, and State of New Jersey, this 21st day of April, A. D. 1915.

FRANK S. TOWNSEND.
